(57) **CLAIM**

The ornamental design for a robot, as shown and described.

DESCRIPTION

FIG. 1 is a front view of a robot, showing our new design;
FIG. 2 is a rear view thereof;
FIG. 3 is a top plan view thereof;
FIG. 4 is a bottom view thereof;
FIG. 5 is a right side view thereof;
FIG. 6 is a left side view thereof;
FIG. 7 is a front perspective view thereof; and,
FIG. 8 is a rear perspective view thereof.

The broken line showings in each of the respective drawing figures of elements in the regions of the hands, ankles and pelvic region of the robot are for illustrative purposes and form no part of the claimed design.

1 Claim, 5 Drawing Sheets
